APPARATUS FOR RAILWAY COMMUNICATION SYSTEMS

Andrew J. Sorensen, Edgewood, Pa., assignor to
The Union Switch & Signal Company, Swiss-
vale, Pa., a corporation of Pennsylvania

Application September 20, 1934, Serial No. 744,814

13 Claims. (Cl. 246—8)

My invention relates to apparatus for railway communication systems, and particularly to railway train telephone systems.

I will describe two forms of apparatus embodying my invention, and will then point out the novel features thereof in claims.

It has been proposed in the United States application for Letters Patent, Serial No. 450,135, filed May 6, 1930, by L. O. Grondahl, for Electric train signaling systems, to utilize the traffic rails in multiple as the communication channel for transmitting a communication current between locations on two different trains, or between two spaced locations on the same train, or between a wayside station and a location on a train, the communication current being preferably in the form of a modulated carrier current, such as, for example, a carrier telephone current.

At each location of such communication system a transmitting device and a receiving device are provided, together with an inductor adapted to be connected with either of said devices, and which inductor is disposed in inductive relation with the traffic rails. When the inductor of a location is connected with the transmitting device at the same location and communication current supplied thereto, an electromotive force of a corresponding frequency is induced in the traffic rails, and as a result of such electromotive force, current flows in the rails in multiple in both directions from the point of induction and returns through the ground. When the inductor is connected with the receiving device at the same location it is effective to inductively receive an electromotive force in response to such communication current flowing in the rails.

It has been found that line wires and other conductors paralleling the traffic rails in which such communication current is induced, through their distributed capacity with ground and with the traffic rails and through their inductive relationship with the inductor, are also effective in carrying the communication current. That is to say, line wires and conductors paralleling the traffic rails act in conjunction with the traffic rails to form a communication channel. I have found that at a distance equal to the length of the usual freight train from an inductor transmitting current, a line wire extending along the right-of-way may be carrying several times as much of the communication current as any one of the rails, notwithstanding the fact no apparatus for coupling such line wires and the rails is provided.

It has also been proposed to mount the induct-

tors on the vehicle of a train relatively high above the rails and in a plane to link a magnetic field transverse to the track in order to increase the inductance of the inductor to line wires extending along the right-of-way.

Apparatus for cooperatively using line wires and the traffic rails as a communication channel is disclosed and claimed in a copending application for Letters Patent, Serial No. 696,663, filed November 4, 1933, by P. N. Bossart, for Railway communicating systems; and in a copending application for Letters Patent, Serial No. 72,605, filed April 3, 1936, by P. N. Bossart for Railway train communication systems. My present application may be considered as an improvement on the above cited Bossart applications.

A feature of my invention is the provision of apparatus for coupling one or more line wires to the traffic rails at selected intervals to increase the amount of communication current that will flow in such line wires and thereby improve the operation of the communication system. A further feature of my invention is the provision of apparatus for coupling existing line wires with the traffic rails in such a way that a low impedance path is provided for the communication current while the wayside circuits in which these line wires ordinarily form a part are undisturbed. To put it another way, a feature of my invention is the provision of apparatus operative to transfer communication current induced in the traffic rails to a line circuit near the location of the transmitting inductor, carry such current along line wires having relatively low impedance for the current, and then transfer the current from the line circuit back to the traffic rails near the location of the receiving inductor. The line circuit will be constantly effective notwithstanding the fact both the transmitting and receiving inductors may be mounted at the opposite ends of a train and hence move along the rails as the train advances. Furthermore, the line circuit will be preferably made up of existing line wires which form a part of existing circuits independent of the communication system.

In the accompanying drawing, Fig. 1 is a diagrammatic view of one form of apparatus embodying my invention and wherewith the line wires which form a part of a wayside signal control circuit are coupled with the traffic rails at the junction of track sections commonly provided for a wayside signal system. Fig. 2 is a diagrammatic view of apparatus for coupling line wires used as a part of a telegraph circuit with the traffic rails at selected locations along the right-

of-way, which apparatus also embodies my invention.

In each of the two views, like reference characters designate similar parts.

Referring to Fig. 1, the reference characters 10 and 11 designate the respective traffic rails of each of three railway tracks 1, 2 and 3, over which tracks traffic normally moves in the direction indicated by the arrows. Each of the tracks 1, 2 and 3 is divided by insulated rail joints into track sections, such as are customarily provided for wayside signal systems. The associated wayside signal system is not shown in the drawing for the sake of simplicity since it may be of any of the standard types and since it constitutes no part of my present invention.

In this instance, only two complete track sections A—B and B—C are shown for each of the tracks, and it will be understood that each of the three tracks will be divided into similar sections for the full length of a given stretch of the railway. The track sections A—B and B—C for the track 1 are each provided with a track circuit which, in the case of section A—B, consists of a source of current such as a battery 12 connected across the traffic rails 10 and 11 at the outgoing end of the section, and a track relay designated by the reference character R_A connected across the traffic rails at the entrance of the section. In like manner the track circuit for the section B—C includes a battery 12 connected across the rails at the right-hand end of the section and a relay R_B connected across the rails at the left-hand end of the section. Each of the remaining track sections will be provided with a similar track circuit. These track circuits control over contacts operated by the track relay circuits used in connection with the wayside signal system. For illustration, the track circuit for the section A—B of track 1 governs over a front contact 14 of its relay R_A, an approach control circuit which consists of a battery 13 located at the left-hand end of the section, two line wires W1 and W2 extending the full length of the section and a relay designated by the reference character V_B located at the right-hand end of the section. In like manner the track circuit for the section B—C of track 1 governs a similar approach control circuit including a battery 22, two line wires W3 and W4 and a relay V_C. Furthermore, each of the remaining track circuits associated with the successive sections for the track 1 will govern an approach control circuit similar to the control circuits just described in connection with the sections A—B and B—C. These several approach control circuits will ordinarily govern apparatus in connection with the wayside signal system, but the significant feature about such circuits in connection with the present invention is merely the fact that the successive circuits provide a pair of line wires which extend the full length of the track 1, but which terminate at signal locations.

To combine the line wires of these approach control circuits associated with the track 1 into a continuous circuit extending along a stretch of the railway, and which circuit may be utilized as a part of the communication channel for a train communication system independent of the wayside signal system without interfering in any way with their function in connection with the wayside signal system, I provide a transformer T and resistors at each of several signal locations. At location A, a transformer T_A consisting of three windings 14, 15 and 16, together with sev-

eral resistors are provided. The winding 14 is interposed in the approach control circuit associated with the track section to the left of the location A by being connected between the winding of the relay V_A and the line wire W6. The winding 15 of the transformer T_A is interposed in the approach control circuit associated with the section A—B by being connected between the battery 13 and the line wire W2. The winding 16 of the transformer T_A has one terminal connected with a ground electrode 17 and its other terminal connected with the traffic rails of each of the three tracks 1, 2 and 3, resistors 18 and 19 being interposed between the winding and the traffic rails of the track 1, resistors 42 and 44 being interposed between the rails of the track 2 and the winding, and resistors 40 and 45 being interposed between the traffic rails of the track 3 and the winding, as will be readily understood by an inspection of Fig. 1. A resistor 21 is connected between the terminal of the winding 14 adjacent the winding of the relay V_A and the terminal of the winding 15 adjacent the battery 13. In other words, the transformer T_A has three windings, one of which, 14, is connected in series with the V_A relay at the same location, a second winding of which, 15, is connected in series with the line battery at the same location and the third winding of which, 16, is connected between the traffic rails of each of the different tracks and ground. At location B, a transformer T_B and resistors are provided. Transformer T_B consists of three windings 24, 25 and 26. The winding 24 is connected in series with the relay V_B, the winding 25 is connected in series with the battery 22, while the winding 26 is connected between the ground electrode 27 and the traffic rails over resistors, in a manner similar to that just described in connecting the windings of the transformer T_A. A resistor 30 at location B connects the two adjacent terminals of the windings 24 and 25 of transformer T_B in the same manner the resistor 21 at location A connects the two windings 14 and 15 of the transformer T_A. At location C a transformer T_C is provided, which has three windings 31, 32 and 33 similar to the windings of the two transformers T_A and T_B. These windings of transformer T_C are connected with the approach control circuits and between the traffic rails and ground in the same manner as described hereinabove in connection with the transformers T_A and T_B, and it is thought unnecessary to repeat their description in detail.

With the impedances of the first two windings of each of the transformers, that is, windings 14 and 15 of transformer T_A, windings 24 and 25 of transformer T_B and windings 31 and 32 of transformer T_C, properly adjusted, and a proper selection of the resistors 21, 30 and 34, communication current will flow freely from one approach control circuit to the next by a line circuit which is continuous for the full length of a given stretch of the railway. Starting with the line wire W6 at the left-hand end of Fig. 1, this continuous circuit can be traced over winding 14 of the transformer T_A, resistor 21, winding 15, line wire W2, winding 24 of transformer T_B, resistor 30, winding 25, line wire W4, winding 31 of transformer T_C, resistor 34, winding 32 and thence over the line wire W8. It will be understood that the line wires W6, W2, W4 and W8 each possesses distributed capacity with ground, such capacity being visualized in Fig. 1 by the fictitious condensers 46, 47, 48 and 49, respectively. It follows, therefore, that a modulated carrier current in-

duced in the above-traced line circuit at any one of the transformers will flow from that transformer and return through the distributed capacities and ground.

5 The third winding of each of the transformers, that is, windings 16, 26 and 33 of the transformers T_A, T_B and T_C, respectively, is wound to give the proper transfer of communication current flowing from the traffic rails to ground to the above-traced line circuit, or on the other hand to transfer such current flowing in the line circuit to the traffic rails. For example, communication current flowing from the rails of track 1 over resistors 19 and 18, winding 16 of transformer T_A and thence to ground at 17, will induce electromotive forces in the windings 14 and 15 which will cause a corresponding current to flow in the line circuit including the line wires W6, W2, W4, etc., the return path for this latter current being completed through the distributed capacity of the line wires and ground. Again, communication current flowing in the windings 14 and 15 of transformer T_A will induce an electromotive force in the winding 16 which will set up a current that will flow to the rails of track 1, through the distributed rail to ground resistance, and thence over ground electrode 17 back to winding 16. Since the winding 16 is connected with the rails of tracks 2 and 3 in multiple with its connection with the rails of track 1, it follows that a transfer of communication current from the rails of either track 2 or 3 to the line circuit will be accomplished in exactly the same manner as just described for track 1. A transfer of communication current between the rails of tracks 1, 2 or 3 and the line circuit will be accomplished in like manner at each of the other transformers T_B and T_C. Hence, each of these transformers located at selected locations will be operative to transfer the communication current from the rails to the line circuit when a train-carried inductor transmitting current is in the vicinity of that transformer and will be operative to transfer the current from the line circuit back to the traffic rails in the vicinity of the inductor functioning as a receiver.

For reasons to appear hereinafter the third windings of adjacent transformers are preferably reversed with respect to one another. These 50 third windings and the resistors associated therewith are so proportioned and adjusted that interference with the wayside signal system is avoided.

K represents a train occupying the track 2 and on the front end of which train an inductor 35 is mounted and on the rear end of which a second inductor 36 is mounted. Associated with each of these inductors 35 and 36 will be a transmitting device and a receiving device of a communication system such as referred to hereinabove, for two-way communication between these two spaced locations on the train K. Assuming the inductor 35 to be connected with its associated transmitting device for inducing an electromotive force in the traffic rails corresponding in frequency to the communication current supplied to such inductor, it is clear that current in response to such electromotive force will not only flow in the two rails in multiple from the point of induction and return over the ground path described in the above-mentioned Grondahl application, but such current will also flow along the traffic rails to the right and pass to ground over the path including resistor 37, resistor 38, winding 33 of the transformer T_C and the ground elec-

trode 39, and thence return to the rails of track 2 over electrode 27, winding 26 of transformer T_B and resistors 50 and 51, a portion of the current, of course returning to the rails over the distributed rail to ground resistance. The effect of such current flowing in the winding 33 of transformer T_C will be to induce electromotive forces in the windings 31 and 32 of that transformer. That portion of the current flowing in the winding 26 of transformer T_B will also induce electromotive forces in the windings 24 and 25 of that transformer. Since the windings 26 and 33 of transformers T_B and T_C are reverse with respect to each other the electromotive forces induced in the windings 24 and 25 of transformer T_B and in the windings 31 and 32 of transformer T_C will add their effects and will set up a flow of communication current along the line wires W6, W2, W4 and W8, the return path being through the distributed capacities of the line wires and ground. Such communication current flowing in the windings 14 and 15 of transformer T_A will induce an electromotive force in the winding 16, which will in turn set up a flow of current that passes to ground at 17 on one side and will flow to ground on the other side over resistors 42 and 44, traffic rails of track 2 and the path including the third winding of the transformer at the location next to the left of location A, a portion of the current of course flowing to ground through the distributed rail to ground resistance of track 2 and also of the other tracks. This latter current flowing in the traffic rails of track 2 at the left of location A will be effective along with the communication current flowing in the rails of track 2 in accordance with the above-mentioned Grondahl application to induce an electromotive force in the inductor 36 at the rear end of the train, with the net result that the energy picked up by the inductor 36 for energizing the associated receiving device will be materially increased. It follows that communication current supplied to the rails through the medium of inductor 35 will be transferred to the line circuit in the vicinity of that inductor and will be transferred back to the rails at selected locations, the major portion in the vicinity of the receiving inductor 36.

At such time as the inductor 36 is connected with its associated transmitting device to supply communication current to the traffic rails, such current will flow to ground at 17 over the path including winding 16 of transformer T_A to induce electromotive forces in windings 14 and 15 and communication current will be set up in the line circuit which will travel along the line wires W2, W4 and W8. This current will now induce an electromotive force in the winding 26 of transformer T_B and in the winding 33 of transformer T_C which in turn will cause current to flow to the rails of track 2 and effectively influence the inductor 35, that inductor being now connected with its receiving device.

It is clear that such communication current flowing in the different line wires will be ineffective to influence any one of the individual approach control circuits since such circuits are operated by direct current whereas the communication current is of relatively high frequency. Furthermore, it is clear that current from a line battery such as the battery 22 will not flow to the approach control circuits adjacent its own circuit.

The above-traced line circuit including the line wires W6, W2, W4 and W8 will function to transmit communication current in connection with 75

the tracks 1 and 3, since the third winding of each of the several transformers is connected with the traffic rails of each of these tracks by proper resistors. It will be clear that another control circuit associated with the wayside signal system for the tracks 2 and 3 may also be made to function in connection with transmitting the communication current should it seem desirable to do so.

10 A great advantage in using wayside signal circuits such as shown in Fig. 1, is that these circuits always terminate in instrument cabinets along the right-of-way and no long runs of wire are necessary. If such wayside signal circuits 15 are not available, it is feasible, however, to use a pair of telegraph wires belonging to the same circuit. In Fig. 2, the wires W9 and W10 designate two line wires of a telegraph circuit extending along the railway tracks 1, 2 and 3. In this 20 instance, the transformer Ta provided at the location A has its first winding 14 interposed in the line wire W10 and its second winding 15 interposed in the line wire W9 while its third winding 16 is connected between the ground 17 and the 25 traffic rails of the tracks 1, 2 and 3 in exactly the same manner as in Fig. 1. In this case, the windings 14 and 15 are so disposed that current flowing in the respective line wires W9 and W10 in opposite directions, such as the telegraph current 30 rent, will create fluxes that cancel each other. Consequently, a current flowing in the same direction in both wires and hence in both windings 14 and 15 will create fluxes that are additive, and will induce an electromotive force in the winding 16 which will set up a current flowing between the ground and the traffic rails of the several 35 tracks. Again, communication current flowing from the rails to the ground through the winding 16 will be effective to create electromotive forces 40 in the windings 14 and 15 which will cause a current to flow in the two wires W9 and W10 in multiple. The transformer Tb provided at location B has its three windings 24, 25 and 26 connected with the line wires W9 and W10 and with 45 the traffic rails in exactly the same manner as just described in connection with the transformer Ta of Fig. 2. It will be seen, therefore, that the line wires W9 and W10 will function to transmit communication current along the tracks 1, 2 and 50 3 in the same manner as the line circuit of Fig. 1. That is to say, the line wires W9 and W10 of Fig. 2 function to transmit communication current without interference with the telegraph circuit of 55 which they originally form a part.

55 Although I have herein shown and described only two forms of apparatus embodying my invention, it is understood that various changes and modifications may be made therein within the scope of the appended claims without departing 60 from the spirit and scope of my invention.

Having thus described my invention, what I claim is:

1. In combination, a railway track, a train to travel on said track, means located on the train 65 for inducing a communication current in the traffic rails of said track, a line wire extending along the track, a transformer including a first winding interposed in said line wire, a circuit connected between the rails and ground and including a second winding of said transformer, said circuit operative in response to the communication current flowing from rails to ground to induce an electromotive force in said first winding for causing such communication current to flow in the line 70 wire in both directions from said transformer and 75

return through the ground, and signaling means governed by such current flowing in said line wire.

2. In combination, a railway track, a train to travel on said track, means located on the train 5 for inducing a communication current in the traffic rails of said track, a line wire extending along said track to form one side of a control circuit receiving current from a particular source, a transformer including a first winding interposed in said line wire, circuit means connected between the rails and ground and including a second winding of said transformer, said circuit means operative in response to the communication current flowing from the rails to ground to induce an electromotive force in said first winding for 10 causing such communication current to flow in the line wire in both directions from the transformer independent of said particular source, and signaling means governed by such communication current flowing in said line wire. 15

3. In combination, a railway track, a train to travel on said track, means located on the train for inducing a communication current in the traffic rails of said track, a line wire extending along said track to form one side of a control circuit receiving current from a particular source, a transformer including a first winding interposed in said line wire, circuit means connected between the rails and ground and including a second winding of said transformer, said circuit means operative in response to the communication current flowing from the rails to ground to induce an electromotive force in said first winding for 20 causing such communication current to flow in the line wire independent of said particular source over a circuit including the line wire on each side of the transformer and the distributed capacitance between such wire and ground, and signaling means governed by such communication current flowing in said line wire. 25

4. In combination, a railway track, a line wire parallel to the track and adapted to form one side of a circuit receiving current from a particular source, a transformer including a first winding interposed in said line wire, and a circuit connected between the traffic rails of said track and ground and including a second winding of said transformer and said circuit operative in response to a communication current flowing from the rails to ground to induce an electromotive force in said first winding for 30 causing communication current to flow in the line wire in both directions from the transformer independent of said particular source and to inductively receive electromotive force in response to communication current flowing in the line wire for supplying such communication current to the traffic rails. 35

5. In combination, a railway track, a pair of line wires parallel to said track and adapted to form the two sides of a circuit receiving current 40 from a particular source, a transformer including a first winding interposed in one of said line wires and a second winding interposed in the other of said line wires, and a circuit connected between the traffic rails of said track and ground and including a third winding of said transformer and operative in response to a communication current flowing from the rails to ground to induce electromotive forces in said first and second windings effective to cause such communication current to flow in said line wires in multiple independent of the current supplied by said particular source. 45

6. In combination, a railway track, a line wire extending along said track, a plurality of trans- 50

formers spaced apart along the track and each including a first winding interposed in said line wire, and a plurality of circuit means connected between the rails of the track and ground one at 5 each transformer and including a second winding of the respective transformer, each of said circuit means operative in response to a communication current flowing from the rails to ground to induce an electromotive force in the first winding 10 of the respective transformer to cause such current to flow in said line wire in both directions from that transformer and to inductively receive electromotive force in response to such communication current flowing in the line wire, whereby 15 the communication current is transferred from the rails to the line wire at one location and is transferred back to the rails from the line wire at a second location.

7. In combination, a railway track, a pair of 20 line wires parallel to said track and adapted to form the two sides of a control circuit receiving current from a particular source, a plurality of transformers spaced apart along the track and each including a first winding interposed in one 25 of said line wires and a second winding interposed in the other of said line wires, a plurality of circuit means connected between the rails of said track and ground one at each transformer and including a third winding of the respective transformer, each of said circuit means operative in 30 response to a communication current flowing from the rails to ground to induce electromotive forces in said first and second windings of the respective transformer to cause such current to flow in said line wires in multiple independent of said 35 particular source and to inductively receive electromotive forces in response to such communication current flowing in said line wires, whereby communication current is transferred from the 40 rails to the line wires at one location and transferred back to the rails from the line wires at a second location independent of the control circuit.

8. In combination, a railway track, a plurality of control circuits located successively along 45 the track, each of said circuits including a line wire extending along said track, a transformer located at each junction of said successive circuits and including a first winding interposed in the line wire of the circuit to the right of the junction 50 and a second winding interposed in the line wire of the circuit to the left of the junction, a resistor at each junction connected between the two adjacent terminals of the first and second windings of the transformer at the same junction, 55 and a circuit at each junction connected between the rails of said track and ground and including a third winding of the transformer and operative in response to a communication current flowing from the rails to ground to induce electromotive 60 forces in the first and second windings of that transformer for causing such communication current to flow along the line wires of the successive circuits.

9. In combination, a railway track, a train to 65 travel on said track, communication means at each of two spaced locations on the train each operative to induce communication current in the rails or to inductively receive such current in response to communication current flowing in the 70 rails, a line wire extending along the railway, a plurality of transformers disposed along the track and each including a first winding interposed in said line wire, and a circuit means at each transformer connected between the rails and ground and including a second winding of

the respective transformer, whereby communication current induced in the rails at one location of the train will be transferred to the line wire at the transformers relatively close to that location on the train and will be transferred back to the rails from the line wire at the transformer relatively close to the second train location. 5

10. In combination, a railway track, a train to travel on said track, communication means at each of two spaced locations on the train each 10 operative to induce communication current in the rails or to inductively receive such current in response to communication current flowing in the rails, a plurality of control circuits located successively along said track, each of said circuits 15 including a line wire extending along the track, a transformer located at each junction of said successive circuits and including a first winding interposed in the line wire of the circuit to the right of the junction and a second winding interposed in the line wire of the circuit to the left of the junction, a resistor at each junction connected between the two adjacent terminals of the first and second windings of the transformer at the same junction, and a circuit at each junction 20 connected between the rails and ground and including a third winding of the transformer whereby communication current induced in the rails at one location of the train will be transferred to the line wires of the control circuits, transmitted along the line wires of the successive circuits and then transferred back to the rails for influencing the communication means at the second location on the train. 25

11. In combination, a railway track insulated in track sections, a train to travel on said track, communication means at each of two spaced locations on the train each operative to induce communication current in the rails or to inductively receive such current in response to communication current flowing in the rails, a control circuit for each section including a pair of line wires and an individual current source, a transformer at each junction of such track sections including a first winding interposed in the control circuit to the right of the junction and a second winding interposed in the circuit to the left of the junction, a resistor at each junction connected between said first and second windings of the transformer at the same junction; and circuit means at each of such junctions including a resistor connected from the rails of one section to the rails of the next section, a third winding of the transformer at the same junction and ground; whereby communication current induced in the rails of one section by the means at one location on the train will be transferred to the line wires of the control circuit of that location, transmitted along the control circuits independent of the individual current sources and transferred back to the rails of another section from the line wires for influencing the means at the other location on the train. 35 40 45 50 55 60

12. In combination, a railway including a plurality of tracks each of which is insulated into track sections, a train adapted to travel on said tracks, communication means at each of two spaced locations on the train each operative to supply communication current in the rails or to 65 receive such current in response to communication current flowing in the rails, a control circuit for each section of at least one of said tracks which circuit includes a line wire extending the length of the section, a transformer at each 70 75

junction of such track sections including a first winding interposed in the line wire to the right of the junction and a second winding interposed in the line wire to the left of the junction, a resistor at each junction connected between said first and second windings of the transformer at the same junction, a third winding of each transformer each of which has one terminal grounded, and a plurality of parallel circuits at each junction for connecting the other terminal of the third winding of the transformer at the same junction with the traffic rails of each of said tracks, whereby communication current supplied in the rails of a section of any one of said tracks will be transferred to the line wires of the control circuits and transferred back to the rails of another section of the same track.

13. In combination, a railway including a plurality of tracks, a train adapted to travel on said

tracks, communication means at each of two spaced locations on the train each operative to induce communication current in the rails or to inductively receive such current in response to communication current flowing in the rails, a line wire extending along the railway, a plurality of transformers located at spaced points along the railway, a first winding for each transformer interposed in said line wire, and a second winding for each transformer having one terminal grounded, and its other terminal connected with the traffic rails of the different tracks in parallel, whereby communication current induced in the rails of any one of said tracks will be transferred to the line wire in the vicinity of the point of induction and transferred back to the rails at a remote point.

ANDREW J. SORENSEN. 20
